Primary Examiner — Derrick E Holland*Assistant Examiner* — Jennifer O King(74) *Attorney, Agent, or Firm* — Porter, Wright, Morris & Arthur, LLP.(57) **CLAIM**

The ornamental design for a utility tote panel insert, as shown and described.

DESCRIPTION

FIG. 1 is a front perspective view of a utility tote panel insert, wherein the utility tote panel insert is in a folded configuration;

FIG. 2 is a rear view thereof;

FIG. 3 is a front view thereof;

FIG. 4 is a top view thereof;

FIG. 5 is a bottom view thereof;

FIG. 6 is a left-side view thereof;

FIG. 7 is a right-side view thereof;

FIG. 8 is a top perspective view of the utility tote panel insert of FIGS. 1 to 7, but wherein the utility tote panel insert is in a flat or unfolded configuration;

FIG. 9 is a bottom perspective view thereof;

FIG. 10 is a top view thereof;

FIG. 11 is a bottom view thereof;

FIG. 12 is a rear view thereof;

FIG. 13 is a front view thereof; and,

FIG. 14 is a left-side view thereof, the right side view being a mirror image thereof.

The broken lines in the figures indicate stitching and form a part of the claimed design.
